COMBINED RETURN TOP AND GAME DEVICE

Willy Chelman, Brussels, Belgium, assignor to I.D.
Innovations & Diffusions S.A., Brussels, Belgium

Filed June 30, 1972, Ser. No. 267,742

Claims priority, application Switzerland Mar. 9, 1972

Term of patent 14 years

Int. Cl. D21—01

U.S. Cl. D34—15 AH

FIG. 1 is a perspective view of a first side of a combined return top and game device;

FIG. 2 is a perspective view of the second, opposed side of a combined return top and game device;

FIG. 3 is an elevational view of the first side of a combined return top and game device;

FIG. 4 is an elevational view of the second, opposed side of a combined return top and game device; and

FIG. 5 is an end view of a combined return top and game device.

I claim:

The ornamental design of a combined return top and game device, substantially as shown.
